[57] CLAIM

The ornamental design for a toothbrush holder or similar article, substantially as shown and described.

DESCRIPTION

FIG. 1 is a front perspective view of a toothbrush holder or similar article showing my new design;

FIG. 2 is a rear perspective view thereof;

FIG. 3 is a front elevational view taken in the direction

of arrow 3 of FIG. 5;

FIG. 4 is a rear elevational view taken in the direction

of arrow 4 of FIG. 5;

FIG. 5 is a side elevational view taken from the right of

FIG. 1, the side opposite being a mirror image thereof;

FIG. 6 is a top view taken in the direction of arrow 6 of

FIG. 4;

FIG. 7 is a bottom view taken in the direction of arrow

7 of FIG. 4.

FIG. 1.

FIG. 2.

FIG. 3.

FIG. 4.

FIG. 5.

FIG. 6.

FIG. 7.
